[57] **CLAIM**

The ornamental design for a pair of rear lights for an automobile, as shown and described.

DESCRIPTION

FIG. 1 is a front, left side perspective view of a pair of rear lights for an automobile showing our new design; FIG. 2 is a front elevational view of the left hand light, the right hand light being omitted for convenience of illustration; FIG. 3 is a left side perspective view of the left hand light; FIG. 4 is left side perspective view of the left hand light; and, FIG. 5 is a front perspective view of the left hand light. The right hand rear light is a mirror image of the left hand light shown in FIGS. 2 through 5. The automobile is shown in broken lines for illustrative purposes only.
